UNITED STATES PATENT OFFICE

ERNEST W. CLARK, OF HARTFORD, AND CARL SCHRAMM, OF WEST HARTFORD, CONNECTICUT, ASSIGNEES TO THE SMYTH MANUFACTURING COMPANY, OF HARTFORD, CONNECTICUT, A CORPORATION OF CONNECTICUT.

BOOK SIGNATURE FEED

Application filed August 13, 1928. Serial No. 299,160.

This invention relates to a mechanism for feeding signatures to a book stitching machine of the type illustrated and described in United States patent to Bischof No. 5 1,485,905, March 4, 1924, in which machine the signatures are opened and placed by the operative one at a time on a saddle from which the signatures are automatically fed to an arm, which upon receiving a signature swings inward and carries the folded edge of the signature into position to be stitched to the preceding signatures.

The object of the invention is to provide a feeding mechanism for a machine of the 15 class mentioned which will transfer the signatures from the saddle to stitching position very rapidly and place them accurately so that they will be correctly stitched.

Generally the mechanism comprises a 20 fixed saddle with a pusher which is raised and moved along the top of the saddle to push a signature from the saddle to the oscillatory arm, and then is lowered so as to return beneath the next signature placed on 25 the saddle. A fixed guide is located over the top of the saddle to direct the signatures onto the arm and an oscillatory guard is arranged back of the saddle to prevent the operative from placing a signature on the 30 saddle in feeding position before the preceding signature has been fed therefrom. The oscillatory arm carries a stop and a gauge for accurately locating the signature on the arm and it also carries a leveler that 35 presses the folded edge of the signature down onto the top of the arm and then is raised as the arm carries the signature into stitching position so as to be out of the way of the needles. A guard oscillates toward 40 and from the back of the arm to control the rear signature leaves, and a finger is arranged in front of the arm to control the front leaves of the signature.

In the accompanying drawings Fig. 1 45 shows an elevation looking toward the swinging arm end of the signature feed mechanism. Fig. 2 is a front elevation of the same. Fig. 3 is a view on larger scale looking toward the swinging arm with parts omitted to expose the operating mechanism.

Fig. 4 is a view looking toward the arm from the opposite direction. Fig. 5 is a front elevation showing the adjacent ends of the swinging arm and fixed saddle. Fig. 6 is an elevation looking toward the back of 55 a portion of the arm showing the signature stop and locating gauge carried thereby. Fig. 7 is a top view of a portion of the swinging arm and the leveler and its operating mechanism carried thereby. Fig. 8 is 60 an elevation looking toward the saddle end of the machine. Fig. 9 is a front elevation of the saddle with the front plate removed to expose the pusher. Fig. 10 is a longitudinal section, indicated by the dotted line 65 10—10 on Fig. 11, showing the means for connecting the pusher with its reciprocating mechanism. Fig. 11 is a transverse section, indicated by the dotted line 11—11 on Fig. 10, showing the pusher connecting means. 70

The operative opens a signature and places it on the saddle which is formed of two angularly related plates with the apex at the top. The front plate 1 is fastened to a frame 3 and the rear plate 2 is fastened 75 to a frame 4, which frames are secured to a bracket 5 that is attached to the main frame of the sewing machine, Fig. 8. There is a narrow space between the upper edges of the plates, and the front plate extends 80 slightly above the rear plate so that the upper corner of the front plate forms the apex of the angle at which the plates are arranged.

The pusher 6 is reciprocated through the 85 space between the plates at the apex of the saddle and it is raised above the top of the saddle before it starts to push a signature from the saddle and after it has delivered the signature it is lowered and returned below the top of the saddle so that it will pass beneath the next signature placed on 90 the saddle. The pusher is a thin plate and it is pivoted by stud 7 to a block 8 that is detachably connected by a spring pressed 95 pin 9 with a plate 10 which is fastened to a slide 11, Figs. 10, 11. There are several notches in the plate 10 for receiving the pin 9 so that the block may be set forward or back depending upon the size of the signa- 100

tures, and should any obstruction be offered to the forward movement of the pusher, as by the jamming of a signature, the pin snaps from the notch with which it is engaged and thus disconnects the pusher from the slide which can then move without causing any of the parts to become broken or damaged.

The slide is mounted to reciprocate on a round bar 12 that extends longitudinally beneath the front plate of the saddle and is held at its ends by brackets 13 fastened to the frame 4 which supports the back saddle plate, Fig. 9. The slide in its travel is guided and prevented from turning by the surface of a plate 14 that is fastened to the frame, Fig. 11. A rod 15 extends across the front of the machine and connects the slide 11, Fig. 9, with a bell-crank lever 16, Fig. 2, which by an adjustable link 17 is connected with a lever 18 that is pivoted on shaft 19 and that carries a roll 20 engaged with a cam 21 on the main cam shaft 22 of the machine, Fig. 1. This mechanism causes the reciprocation of the pusher at the proper intervals.

A stud 23 extends from the rear side of the pusher into a groove 24 formed lengthwise in a plate 25 that is mounted to reciprocate longitudinally and also move up and down, Figs. 9, 11. This plate is located beneath the rear saddle plate and has two cam grooves 26 lying in which are rolls 27 mounted on plates 28 that are fastened to the frame 4, Fig. 9. The cam grooves are so shaped that when the plate is moved forward it is raised and when it is moved backward it is lowered, and as the pusher is connected with this plate by the stud 23 and groove 24 the pusher swings up when the plate is moved forward and down when the plate is moved backward. This plate is engaged by a bell-cranned lever 29 that is connected by a link 30, Fig. 9, with a lever 31 which at the proper time is oscillated by a cam 32, Fig. 2, on the main cam shaft of the machine. When the pusher is retracted to its starting position it is lifted by the forward and upward movement of plate 25 so as to project above the top of the saddle. The pusher moves in its upper position along the length of the saddle and pushes a signature onto the swinging signature arm, then shortly after the pusher starts to return the plate moves backward and downward and draws the pusher beneath the top of the saddle in which position it remains until reaching its starting end, where it is again raised.

As the pusher moves forward a guard 33 back of the saddle swings forward and holds the signature leaves from flying out. This guard is attached to a bell-crank lever 34 which is pivoted to the saddle supporting bracket 5, Fig. 8, and which is connected by

a link 35 with a lever 36 that is actuated at the proper time by cam 37 on the main cam shaft, Fig. 2. The guard stands away from the saddle when the pusher is back and swings up to guard and guide the inner signature leaves just as the pusher starts forward, and it remains near the saddle until the signature has been pushed onto the arm and then it swings away, reaching its outer position as the pusher delivers the signature onto the arm. At the top of the guard is a rearward projection 38, Fig. 8, which stands out so as to obstruct the placing of a signature on the saddle before the proper time.

A funnel-shaped guide 39 having a short front leg 40 and a long rear leg 41 is arched over the end of the saddle that is adjacent to the arm, Figs. 5, 8. This funnel is attached to the frame of the machine and is designed to guide the signature from the saddle onto the arm. Adjustably attached to the guide 39 so as to form a continuation thereof over the end of the arm is an arched guide 42, Figs. 4, 5.

The swinging arm comprises a head 43 with a front plate 44 and a rear plate 45, Fig. 4, that have their upper edges notched, Figs. 5, 6, and that are arranged at the same angle with each other as the saddle plates 95 and have a space at the apex into which the pusher advances sufficiently to push the signature 46 from the saddle onto the arm. The arm head is fastened to the upper ends of two rockers 47, Figs. 3, 4, that are fastened to a rock shaft 48 which extends across the front of the machine frame. The other end of each rocker is engaged by a cam 49, Figs. 1, 2, shaped to swing the arm from alignment with the saddle into stitching position after the pusher leaves it and is returning. In the arm is the usual looping mechanism which cooperates with the needle mechanism for forming the loop when a signature is being stitched. As the looping mechanism is set forth in the patent above referred to and is not a feature of the present invention it is not illustrated or described herein.

The pusher advances the signature slightly 115 beyond stitching position into engagement with a stop 50 attached to a spring plunger 51 mounted in a slide 52. The slide is adjustable along a dovetail way 53 fastened to the back plate 45, and is located in place by a pin 54 carried by the slide and adapted to engage the notches 55 in the way, Fig. 6. The stop is pushed back by the advancing signature and then when the pusher is returned and the pressure is relieved the stop pushes the signature back against a heading gauge 56, Fig. 6. The stop shown is on the inside of the arm, there may however be a similar stop on the outside of the arm.

As the arm swings back and carries the 130

signature into stitching position the heading gauge 56, Fig. 6, is given a slight movement sidewise so as to accurately locate the signature on the arm. The heading gauge is adjustably attached to a slide 57 which is movable on the way 53 on the inside of the rear plate. The slide 57 is moved by a lever 58 which is actuated as in the machine of the aforesaid patent.

10 The leveler 59 is a concave plate which extends lengthwise over the top of the signature carrying arm and is designed to press down and retain the folded edge of the signature on the top of the carrying arm from feeding position until just before stitching position is reached. The leveler has an axis 60 at one end which is rotably mounted in the upper end of a lever 61 that is pivoted at 62 to one of the arm rockers 47, so that 15 the leveler swings with the arm, Figs. 3, 7. Fastened to the outer end of the leveler axis are two fingers 63 and 64 provided with rolls 65 and 66.

20 The lever 61 that carries the leveler has a roll 67 that lies in a cam groove 68 in the inside of a bracket 69 attached to the machine frame, Fig. 3. A portion of this cam groove is concentric with the axis 48 of the rocker 47 so that while the roll is passing through this section of the cam groove the lever 61 travels with the rocker as one part. The inner end of the cam groove turns up so that as the rocker with the leveler approaches stitching position the cam groove 25 will cause the lever 61 to oscillate independently of the rocker and turn the leveler out of the path of the needles as the arm reaches stitching position, which position is indicated by dotted lines in Fig. 3.

30 Fastened to the outer end of the bracket 69 is a cam 70, Fig. 3, and as the arm reaches its outer position the roll 66 on the finger 64 fastened to the axis 60 of the leveler, engages this cam and causes the leveler to 35 swing up from the top of the arm so as to be out of the way of the signature that is fed by the pusher from the saddle onto the arm. As the arm swings forward this roll passes out of contact with the cam surface 40 and allows the spring 71, Figs. 3, 7, to turn the leveler down so that it will press the folded edge of the signature down upon the top of the arm. A stop screw 72, Fig. 7, is arranged to limit the downward movement 45 of the leveler as it is pulled by the spring. 50 Fastened to the end of the head of the arm is a cam 73, Figs. 1, 3, which is engaged by the roll 65 on the finger 63 that is fastened to the axis 60 of the leveler. As long as the 55 lever 61 which carries the leveler moves as one piece with the arm rocker 47, that is while the roll 67 is traveling in the first part of the cam groove 68, the roll 65 remains in one position on the cam 73, but 60 when the roll 67 reaches the active portion

65 of the cam groove 68 so that the lever 61 is turned independently of the rocker 47 the roll 65 rides on the cam 73 in such a manner as to lift the rocker. This occurs as the arm approaches stitching position for the purpose of lifting the leveler so that the leveler can be swung back out of the way of the needles without dragging the upper edge of the signature out of stitching position.

70 Extending across and adjacent to the inner face of the arm is a guide 74 at the upper end of a rod 75 that is yieldingly clamped to a lever 76 which is pivoted on the rock shaft 48, Figs. 3, 4, and is actuated at the proper times by a cam 77 on the main 75 cam shaft, Fig. 2. This guide retains the back leaves of the signature in place on the arm besides guiding them when they are advanced by the pusher onto the arm. It 80 clamps the leaves for an interval after the 85 signatures have been located by the heading gauge and while the leveler is being lifted.

Below the swinging arm at the front is a bar 78, Figs. 2, 4, which is fixed to and extends horizontally from the frame 3 into 90 position to support long signature leaves and prevent them from curling around under the arm. Adjustable fastened to a stud 79 held by a bracket 80 to which the guide 42 is fastened, is a yielding finger 81, Figs. 95 4, 5, that extends across the front of the arm and is designed to keep the leaves against the front of the arm as they are fed thereto.

100 After the machine has stitched the fed signature to the preceding signatures, the arm swings out into alignment with the saddle, pulling underneath the outer leaves of the signature that has just been stitched, and the operations are repeated.

105 The invention claimed is:

1. Mechanism for feeding signatures to a book stitching machine comprising a fixed saddle formed of angularly arranged plates with the apex at the top and a space between their upper edges, a pusher movable along the space at the apex of the saddle, mechanism for raising the pusher above the apex of the saddle and moving it forward and for lowering the pusher below the apex 110 of the saddle and moving it backward, a swinging arm formed of angularly arranged plates, and mechanism for moving the arm back and forth from alignment with the saddle to stitching position.

115 2. Mechanism for feeding signatures to a book stitching machine comprising a fixed saddle, a slide adapted to reciprocate below the top of the saddle, a pusher movable along the top of the saddle, a frictional retained connection between the pusher and said slide, mechanism for raising the pusher above the top of the saddle and for lowering the pusher below the top of the saddle, a 120 swinging arm, and mechanism for moving

- the arm back and forth from alignment with the saddle to stitching position.
3. Mechanism for feeding signatures to a book stitching machine comprising a fixed saddle, a slide adapted to be reciprocated below the top of the saddle, a sliding plate adapted to be raised and lowered below the top of the saddle, a pusher pivoted to said slide and engaging said plate whereby it is reciprocated by the slide and oscillated by said plate, a swinging arm, and mechanism for moving the arm back and forth from alignment with the saddle to stitching position.
4. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, and means for pressing down and leveling the folded edge of the signature on the arm.
5. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, and a leveling plate carried by and movable toward and from the top of said arm.
6. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, a leveling plate pivotally mounted on said arm and means for oscillating said leveling plate toward and from the top of the arm.
7. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, a lever pivotally mounted on said arm, a leveler pivotally mounted on said lever, means for oscillating said lever independ-
- ently of said arm and means for oscillating said leveler independently of said lever.
8. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, and a yielding stop and movable heading gauge mounted on said arm.
9. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, means for leveling the signature on the arm, and an oscillatory guide and clamp movable toward and from the back of said arm.
10. Mechanism for feeding signatures to a book stitching machine comprising a fixed saddle formed of angularly arranged plates with the apex at the top and a space between their upper edges, a pusher movable along the space at the apex of the saddle, mechanism for raising the pusher above the apex of the saddle and moving it forward and for lowering the pusher below the apex of the saddle and moving it backward, a swinging arm formed of angularly arranged plates, mechanism for moving the arm back and forth from alignment with the saddle to stitching position, a guide arched over and fixed with relation to the apex of the saddle at one end, and an oscillatory guard movable toward and from the rear of the saddle.
11. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, means for leveling the signature on the arm, and an adjustably mounted friction finger extending across the front of said arm.
12. Mechanism for feeding signatures to a book stitching machine comprising a fixed saddle formed of angularly arranged plates with the apex at the top and a space between their upper edges, a pusher movable along the space at the apex of the saddle, mechanism for raising the pusher above the apex

- of the saddle and moving it forward and for lowering the pusher below the apex of the saddle and moving it backward, a swinging arm formed of angularly arranged plates, mechanism for moving the arm back and forth from alignment with the saddle to stitching position, a guide arched over and fixed with relation to one end of the apex of the saddle, and a guide arched over and adjustable with relation to one end of the apex of the arm. 13. Mechanism for feeding signatures to a book stitching machine comprising a fixed saddle, a pusher movable along the top of the saddle, mechanism for raising the pusher above the top of the saddle and moving it forward and for lowering the pusher below the top of the saddle and moving it backward, a swinging arm, mechanism for moving the arm back and forth from alignment with the saddle to stitching position, a lever pivotally mounted on said arm, a leveler pivotally mounted on said lever, a fixed cam for oscillating said lever independently of said arm, and a fixed cam and a cam on said arm for oscillating said leveler independently of said lever and arm. 14. Mechanism for feeding signatures to a book stitching machine comprising a fixed saddle formed of opposed plates with a space between their upper edges, a pusher movable along said space, mechanism for moving the pusher forward and backward, means movable longitudinally and transversely for raising the pusher above the upper edges of the plates at its backward position and for lowering the pusher below the upper edges of the plates at its forward position, a swinging arm formed of opposed plates approximating the shape of the saddle, and mechanism for oscillating said arm back and forth from alignment with the saddle to stitching position. 15. Mechanism for feeding signatures to a book stitching machine comprising a fixed saddle with a longitudinal slot in its top, a slide adapted to reciprocate below the top of the saddle, mechanism for reciprocating the slide, a pusher pivoted to and movable with said slide, means movable longitudinally below the top of the saddle for swinging the pusher through said slot above and below the top of the saddle as it is reciprocated with said slide, a swinging arm and mechanism for oscillating the arm back and forth from alignment with the saddle to stitching position. 16. Mechanism for feeding signatures to a book stitching machine comprising a fixed saddle with a longitudinal slot in its top, a slide adapted to reciprocate below the top of the saddle, mechanism for reciprocating the slide, a pusher pivoted to and movable with the slide, means movable longitudinally and transversely below the top of the saddle for swinging the pusher through said slot above and below the top of the saddle as it is reciprocated with said slide, a swinging arm, and mechanism for oscillating the arm back and forth from alignment with the saddle to stitching position. 17. Mechanism for feeding signatures to a book stitching machine comprising a fixed saddle formed of opposed plates with a space between their upper edges, a pusher movable along said space, mechanism for reciprocating said pusher, longitudinally and transversely movable means for raising the pusher above the upper edges of the saddle plates at its backward position and for lowering said pusher below the upper edges of said plates at its forward position, and movable means in alignment with the saddle for receiving the books advanced by said pusher.
